UNITED STATES PATENT OFFICE.

AUGUSTUS HOWARD RICHARDSON, OF CHICAGO, ILLINOIS.

FURNACE.

Application filed December 15, 1923. Serial No. 607,041.

To all whom it may concern:

Be it known that I, AUGUSTUS HOWARD RICHARDSON, a citizen of the United States, and a resident of Chicago, in the county of 5 Cook and State of Illinois, have invented certain new and useful Improvements in Furnaces, of which the following is a specification.

In the operation of furnaces, especially 10 those used for burning bituminous coal, it has been found advantageous to provide a supply of air additional to that admitted through the grate and fire bed. This additional or supplemental air has heretofore 15 been introduced into and mixed with the products of combustion at some point above the fire bed in the fire box or in the combustion chamber.

In introducing a supplemental air supply 20 into the partially oxidized products of combustion for the purpose of bringing about complete oxidation it is necessary that the supplemental air be heated to a temperature as high as, or very little below, the 25 temperature of the partially oxidized gaseous and solid products formed above the fire bed. Otherwise the low temperature of the supplemental air will cool the partially oxidized gases and solids in suspension therein, thereby diminishing the combustion that 30 would take place without the supplemental air supply.

Various means have heretofore been resorted to for preheating the supplemental 35 air supply, such means generally including the use of pipes or ducts within the fire box through which pipes or ducts the incoming supplemental air, or mixture of air and steam is conducted before being delivered 40 into the body of partially oxidized gases and suspended carbon. While pipes and conduits, if properly arranged within the fire box, are subjected to a high temperature and are therefore effective to impart a high 45 degree of temperature to air passing through them, they present considerable resistance to the passage of an air current and are not conducive to the effective distribution 50 of the incoming supplemental air throughout and in thorough admixture with the products of partial combustion within the fire box or combustion chamber. Furthermore, such pipes and conduits within the fire box involve considerable complication 55 of structure which is subject to deteriora-

tion and derangement by reason of the high temperature.

It is one of the principal purposes of my invention to thoroughly distribute highly heated supplemental air throughout the partially oxidized products of combustion without the employment of any air pipes or conduits within the fire box. Broadly stated, I effect this purpose by admitting the supplemental air directly to the fire box through 60 openings in the side walls thereof immediately in front of a depending curtain at the back of the fire box, and provide means for spreading the incoming supplemental air over the highly heated fire brick front face 65 of the curtain immediately upon the entrance of the supplemental air and before its admixture with the partially oxidized gases and suspended solids within the fire box. The gases then pass beneath the lower 70 edge of the curtain to the combustion chamber behind the curtain and thence to the flues. Preferably I also provide means for partially preheating the supplemental air by 75 conducting it through conduits outside of 80 the fire box but in proximity to heated parts of the furnace, such as the walls of the ash pit and of one or more of the water sections, before delivering the same to the interior of the fire box as above described. 85

In the drawings

Fig. 1 is a perspective view of a furnace embodying my invention, some of the structure being broken away to better exhibit the remainder;

Fig. 2 is an elevation view of the bridge or curtain section;

Fig. 3 is an elevation view of the section which is provided with admission ports for the supplemental air, and in this view there 95 also appear parts of the external air conduits;

Fig. 4 is a view, partly in section, on the plane indicated by line 4, 4 of Fig. 6, showing part of the water section illustrated in 100 Fig. 3;

Fig. 5 is a section on line 5, 5 of Fig. 2, and

Fig. 6 is a section on line 6, 6 of Fig. 3.

The hot water heating furnace in which I have illustrated my invention comprises a plurality of water sections designated 1 to 12, inclusive, the number of sections varying according to the size of the furnace. The general outline of the water sections is 110.

shown in Figs. 1, 2 and 3. Figs. 2 and 3 show features peculiar to my invention but do not depart otherwise from the form of the other water sections. The top and sides 3 of the fire box and combustion chamber are enclosed by the arched tops and depending legs of the water sections, the water spaces within the several water sections being connected as usual by communicating openings.

- 10 As usual, also, the gases passing to the rear of the furnace rise through suitable ducts and pass forward to the front of the furnace through the flues formed by the openings 13 in the water sections, and thence back to the smoke box at the rear through the flues formed by the openings 14, 15 in the water sections. These features of construction and operation are old and widely used. In applying my invention all of the 15 water sections may be of forms heretofore used with the exception of those designated by the numerals 9 and 10.

The curtain or bridge section, designated by the numeral 10, is separately shown in 25 Figs. 2 and 5. The curtain or bridge 24 in the furnace illustrated is shown as extending downward from the roof arch of the fire box about half-way to the grate, the lower edge of the curtain being at a height sufficient to permit passage of the products of 30 combustion through the space between the lower edge of the curtain and the fire bed, as indicated in Fig. 1. The curtain forms the rear wall of the fire box and restricts 35 communication between the fire box and combustion chamber to the relatively narrow space between the fire bed and lower edge of the curtain. The part of the curtain section extending below the line 25, 40 which defines the roof arch of the fire box, is recessed in its forward surface at 26, as shown most clearly in section in Fig. 5, the outline of the recessed panel being also designated by the numeral 26 in Fig. 2. The 45 recessed panel 26 is filled with refractory material. In the present instance I have shown four fire bricks 27, leaving a marginal space 40 which may be filled with fire clay. The water space 28 extends to the 50 lower edge of the curtain, being thinner opposite the recessed panel owing to the space occupied by the latter.

The water section designated by the numeral 9 is immediately in front of the bridge 55 or curtain section 10 and is provided with air admission ports 18, 18, preferably located at the upper ends of the depending water legs just beneath the roof formed by the arched centers of the water sections, and air deflectors 22 are also formed integrally with water section 9 and project inwardly and rearwardly from the forward sides of the air ports 18. These deflectors 60 preferably extend across the angles between 65 the central arch and depending water legs,

as shown in Figs. 1 and 3. As shown in Fig. 6, the water spaces 20 extend through the water legs 19 at each side of the air ports 18 and also extend throughout the interior of the deflectors 22. The inner part 70 of each of the deflectors 22 is formed with a rearward curvature, as indicated at 23, which curvature or any equivalent rearward inclination of the deflectors, serves to give a rearward direction to the air currents 75 entering through the admission ports 18, thereby deflecting the supplemental air supply against the face of the curtain or bridge 24 above described. Extending upwardly along the outer sides of the legs 19 of the 80 air port section 9 from the lower ends thereof to the air ports 18 are air ducts 21, shown in the structure illustrated as an integral part of the air port section. Extending along the sides of the ash pit from the front 85 of the furnace to the lower ends of the ducts 21 are ducts 29, through openings in the forward ends of which air is drawn in by the furnace draft, and passing through ducts 90 29 and 21, enters the fire box through ports 18 and is then directed against and across the heated face of the forward side of curtain 24. Dampers 30 may be provided to regulate the volume of supplemental air.

Several of the water sections immediately forward of the air port section 9, and the section at the extreme front of the furnace, are similar in external outline to the air port section with the exception, of course, of the omission of the deflectors and air inlet ducts. In the furnace illustrated the sections similar in external contour to the air port section are those designated by the numerals 1, 6, 7 and 8. The water sections designated by the numerals 2, 3, 4 and 5 are provided with narrowed depending parts 2', 3', 4' and 5', respectively, which reduce the effective height of the fore part of the fire box, while the higher arch formed by sections 6, 7 and 8 affords the necessary space for the volume of gases at the rear of the fire box. The water section designated 110 11, immediately behind the water curtain, of which there may be one or more according to the size of the furnace, may be of the same form as sections 1 and 6 to 8, and the section designated 12 is formed with a continuous web which closes, and forms the 115 back wall of, the furnace.

As stated in the introductory part of this specification, it is necessary that the supplemental air admitted to the furnace for the purpose of effecting complete oxidation be highly heated before admixture with the partially oxidized products of combustion. Such heating cannot be effected by contact of the air with the metal water or steam sections of a boiler as the temperature of these parts is constantly lowered by the contained 120 water or steam. It is for this reason that I 125 130

provide the refractory facing of brick or other material upon the forward side of the depending curtain, as above described. This refractory material, being a poor conductor of heat, acquires a very high temperature from the products of combustion which sweep against it and pass along its face to the space beneath the lower edge of the curtain. The deflectors 22 direct the supplemental air entering through ports 18 against and spread it in a sheet over the refractory material which forms the face of the curtain. The incoming supplemental air, therefore, contacts with the highly heated curtain before, or simultaneously with its first contact with the partially oxidized products in the fire box, and the preheating of the supplemental air so effected before its admixture with the partially oxidized products results in producing complete combustion and the elimination of smoke.

It is obvious that my invention is not confined to the particular type of furnace herein described.

25 I claim as my invention:

1. In a fire-box, a curtain forming the rear wall thereof and extending downward from the top thereof to direct the flow of the products of combustion beneath the lower edge of said curtain, and means for admitting air into said fire-box and causing said air to impinge against the forward side of said curtain before admixture thereof with the products of combustion in said fire-box.

2. In a fire-box, a curtain forming the rear wall thereof and extending downward from the top thereof to direct the flow of the products of combustion beneath the lower edge of said curtain, and means for admitting air into said fire-box and causing said air to impinge against the upper part of the forward side of said curtain before admixture thereof with the products of combustion in said fire-box.

3. In a fire-box, a curtain forming the rear wall thereof and extending downward from the top thereof to direct the flow of the products of combustion beneath the lower edge of said curtain, the side walls of said fire-box being provided with air inlet openings forward of and adjacent to said curtain, and deflectors extending inwardly and rearwardly from the forward sides of said inlet openings to direct the flow of air against the forward side of said curtain.

4. In a furnace, a fire-box, a curtain forming the rear wall of said fire-box and extending downward from the top thereof to

direct the flow of the products of combustion beneath the lower edge of said curtain, air inlet conduits extending along the sides of said furnace and communicating with said fire-box adjacent to and forward of the forward side of said curtain, and means within said fire-box for directing the flow of air from said conduits against the forward side of said curtain.

5. In a hot water heating furnace, a fire-box, a plurality of water sections inclosing the sides and top of said fire-box, the rear wall of said fire-box consisting of a depending curtain forming a part of one of said water sections and having a water space therein, one of the water sections forward of said curtain having air inlet openings therethrough, a facing of refractory material on the forward side of said curtain, and deflecting means to direct the air from said inlet openings against said facing of refractory material.

6. In a hot water heating furnace, a fire-box, a plurality of water sections inclosing the sides and top of said fire-box, the rear wall of said fire-box consisting of a depending curtain forming a part of one of said water sections and having a water space therein, one of the water sections forward of said curtain having air inlet openings therethrough, deflectors projecting inwardly from the forward sides of said air inlet openings, said deflectors forming part of said last named section and containing a water space continuous with the water space thereof.

7. In a fire-box, a curtain forming the rear wall thereof and extending downward from the top thereof to direct the flow of the products of combustion beneath the lower edge of said curtain, the side walls of said fire-box being provided with air inlet openings forward of and adjacent to said curtain, and deflectors extending inwardly from the forward sides of said inlet openings to direct the flow of air against the forward side of said curtain.

8. In a fire-box, a curtain forming the rear wall thereof and extending downward from the top thereof to direct the flow of the products of combustion beneath the lower edge of said curtain, the side walls of said fire-box being provided with air inlet openings forward of and adjacent to said curtain, and deflectors to direct the flow of air against the forward side of said curtain.

In witness whereof, I hereunto subscribe my name this 13th day of December, A. D., 1922.

AUGUSTUS HOWARD RICHARDSON.
